[57] CLAIM

The ornamental design for a untethered communications/
media handset, as shown and described.

DESCRIPTION

FIG. 1 is a top, front, and right side perspective of the
untethered communications/media handset showing my new
design, the broken line showings of a hand being for
illustrative purposes only and form no part of the claimed
design;

FIG. 2 shows a bottom rear and right side perspective view
of the untethered communications/media handset;

FIG. 3 shows a front view of the untethered communica-
tions/media handset;

FIG. 4 shows a rear view of the untethered communica-
tions/media handset;

FIG. 5 shows a right side view of the untethered communica-
tions/media handset;

FIG. 6 shows a top plan view of the untethered communica-
tions/media handset; and,

FIG. 7 shows a bottom plan view of the untethered communica-
tions/media handset.
